Primary Examiner — Marissa J Cash*Assistant Examiner* — Kayla Marie Bennett(74) *Attorney, Agent, or Firm* — Daniel M. Cohn; Howard M. Cohn(57) **CLAIM**

The ornamental design for a cover for furniture roller, as shown and described.

DESCRIPTION

FIG. 1 is a perspective view of a cover for furniture roller showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross-sectional view of the cover for furniture roller taken along the line 9-9 in FIG. 3.

The dot-dash broken lines shown in FIG. 3 is for annotative purposes only and form no part of the claimed design.

1 Claim, 9 Drawing Sheets(56)
